POWER TRANSMISSION POLE

Henry Dreyfuss, South Pasadena, Calif., assignor to
Southern California Edison Company, Los Angeles,
Calif., a corporation of California

Filed Jan. 9, 1963, Ser. No. 73,106

Term of patent 14 years

(Cl. D26—12)

FIG. 2.

FIG. 1.

FIG. 6.

FIGURE 1 is a front elevation of the power transmission pole embodying my novel design.

FIGURE 2 is a side elevation thereof.

FIGURE 3 is an enlarged view, taken substantially on the line 3-3 of FIGURE 2.

FIGURE 4 is a top plan view.

FIGURE 5 is a section taken substantially on the line 5-5 of FIGURE 1.

FIGURE 6 is a view taken substantially on the line 6-6 of FIGURE 3.

I claim:

The ornamental design for power transmission pole, substantially as shown.
